UNITED STATES PATENT OFFICE.

HORATIO G. ECKSTEIN, OF PHILADELPHIA, PENNSYLVANIA.

FEED-WATER HEATER.

SPECIFICATION forming part of Letters Patent No. 271,575, dated January 30, 1883.

Application filed November 15, 1882. (No model.)

To all whom it may concern:

Be it known that I, HORATIO G. ECKSTEIN, of the city and county of Philadelphia, and State of Pennsylvania, have invented an Improvement in Feed-Water Heaters, of which the following is a specification.

My invention has reference to feed-water heaters; and it consists in forming a communication between the exhaust and the suction pipe of the boiler feeder or pump without interfering or obstructing the free-exhaust passage to the atmosphere; further, in providing said cold-water or suction pipe with means to filter out the mud, and in details of construction, all of which are fully set forth in the following specification and shown in the accompanying drawings, which form part thereof.

The object of my invention is to provide suitable cheap apparatus to heat the feed-water for the boiler through the agency of the exhaust-steam and without putting a back-pressure upon the engine, and also to prevent the passage of an excess of sediment into the boiler.

In the drawings, Figure 1 is a side elevation of apparatus embodying my improved feed-water heater. Fig. 2 is a plan of same, and Fig. 3 is a sectional elevation of the filter.

A is the steam-engine. B is the usual exhaust. C is the boiler feeder or pump, and may be actuated by the engine, or may be an independent steam-pump. D is the valve-chamber to the pump. E is the cold-water or suction pipe, and connects with the lower part of filter G, which consists of a box or casing provided with lugs g, upon which is hung by flanges i the perforated metal pan I, in which is placed the filtering-sponge. The pan I is made to draw out for cleansing purposes, and when in use the cap or cover G' is bolted on. H is the water-main. The exhaust B is tapped by a pipe, K, provided with a regulating-valve, L, which connects with cold-water-supply pipe E by pipe M. N is an air-chamber to relieve the pump. F is the hot-water feed-pipe.

The operation is as follows: The cold water, after being cleansed in the filter G, is drawn into the pump by the outward movement of the piston and sucks in a quantity of steam from the pipe K, the supply being controlled by valve L. The steam gives up its heat to the water and causes its temperature to rise to almost boiling, when it is forced out by feed-

pipe F to the boiler. Owing to the condensation of the steam, a partial vacuum is produced, thereby increasing the power of the engine, and the pressure of the steam assists the suction of the pump. A double-acting pump may be used, if desired.

I do not limit myself to the exact constructions shown, as they may be modified in various ways without departing from my invention.

I am aware of the English Patent No. 1,059 of 1873, and also American Patent No. 169,332, of 1875, and claim nothing therein set forth or shown.

Having now described my invention, what I claim as new, and desire to secure by Letters Patent, is—

1. In a feed-water heater, the combination of the exhaust-pipe of a steam-engine, unobstructed or at all times open to the atmosphere, with a feed-pump, a supply-pipe to conduct cold water to the pump, a feed-pipe, and a pipe connecting the exhaust with the cold-water-supply pipe, substantially as and for the purpose specified.

2. In a feed-water heater, the combination of the exhaust-pipe of a steam-engine, unobstructed or at all times open to the atmosphere, with the feed-pump, and a pipe connecting said exhaust-pipe with said feed-pump, substantially as and for the purpose specified.

3. In a feed-water heater, the combination of the exhaust-pipe of a steam-engine, unobstructed or at all times open to the atmosphere, with the feed-pump, supply-pipe, and feed-pipe, a pipe opening from the exhaust to supply steam to the suction end of the pump, and means to regulate the supply of steam to said water-supply without interfering with the natural exhaust-passage from the engine, substantially as and for the purpose specified.

4. The combination of engine A, exhaust-pipe B, unobstructed or at all times open to the atmosphere, feed-pump C, water-supply pipe E, feed-pipe F, pipe K, connecting exhaust with suction end of pump, and air-chamber N in the water-supply pipe, substantially as and for the purpose specified.

5. The combination of engine A, exhaust-pipe B, feed-pump C, water-supply pipe E, feed-pipe F, pipe K, connecting exhaust with suction end of pump, air-chamber N in the water-supply pipe, and valve L to regulate the

supply of steam to the water-supply pipe without changing or obstructing the natural exhaust from the engine, substantially as and for the purpose specified.

5 6. The combination of engine A, exhaust-pipe B, unobstructed or at all times open to the atmosphere, feed-pump C, water-supply pipe E, a filter in said supply-pipe, water-main H, feed-pipe F, and pipe K, connecting exhaust with suction end of pump, substantially as and for the purpose specified.

10 7. The combination of engine A, exhaust-

pipe B, unobstructed or at all times open to the atmosphere, feed-pump C, water-supply pipe E, filter G, main H, feed-pipe F, pipe K, connecting exhaust with suction end of pump, air-chamber N, and valve L, substantially as and for the purpose specified.

In testimony of which invention I hereunto set my hand.

HORATIO G. ECKSTEIN.
